[57] CLAIM

The ornamental design for a protective cover for insulated pipes, as shown and described.

DESCRIPTION

FIG. 1 is a perspective view taken from the top and front of a protective cover for insulated pipes showing my new design;

FIG. 2 is a top view thereof;

FIG. 3 is a front view thereof;

FIG. 4 is an end view thereof;

FIG. 5 is a bottom view thereof;

FIG. 6 is a rear view thereof; and,

FIG. 7 is a view taken from the end opposite that shown in FIG. 4.

FIG.1

FIG.2

FIG.4

FIG. 7

FIG. 5

FIG. 6
